SET OF AUTOMOBILE LOUVRE ACCESSORIES

Hyman R. Richter and Robert I. Demaray, Hamilton,
Ontario, Canada, assignors to Bay-King Motors (1968)
Ltd., Hamilton, Ontario, Canada

Filed Aug. 24, 1973, Ser. No. 391,209

Term of patent 14 years

Int. Cl. D12—16

U.S. Cl. D12—155

FIG. 1.

FIG. 2.

FIG. 3.

FIG. 4.

FIG. 5.

FIG. 6.

FIG. 1 is a front elevational view of the right handed automobile louvre accessory showing our new design;

FIG. 2 is a bottom plan view thereof;

FIG. 3 is a right end elevational view thereof;

FIG. 4 is a sectional view thereof taken on the line IV—IV of FIG. 1 and looking in the direction of the arrows;

FIG. 5 is a left end elevational view thereof; and

FIG. 6 is a front elevational view of the left handed automobile louvre accessory, it being understood that the bottom, right end, and left end thereof are mirror images of the corresponding bottom, right end and left end shown in FIGS. 2, 3 and 5 respectively.

The rear of the automobile louvre accessories is substantially unornamented.

We claim:

The ornamental design for a set of automobile louvre accessories, as shown and described.
